In Germany July 18, 1933

6 Claims (Cl. 197—47)

This invention relates to a type wheel typewriter, in which the type wheel is turned by means of an adjusting lever moving over a letter scale and movable parallel to the platen and a rack connected with the lever and engaging a gear coaxial with the type wheel for adjusting the type to be printed, and displaced for printing towards the platen by moving the adjusting lever and simultaneously securing the position of the adjusted type.

In known typewriters of this class the type wheel is arranged on a lever which is moved about a fixed pin for printing the type. This construction suffers from the drawback that, during the printing motion, the adjusting gear with which the type wheel is connected will to a slight extent roll over the rack whereby the adjustment is altered and printing unfavorably affected. Locking of the type wheel as adjusted by inserting, during the printing motion, a tooth of a disc non-rotatably yet axially displaceably coupled with the type wheel and provided with guide teeth on its circumference between two fixed guide tongues having sloping entering ends cannot eliminate this defect, as the point fixed by the guide tongues is located not directly underneath the type to be printed and the motion of the type wheel about the fixed pin is rendered difficult at least if the type wheel is prevented from lateral motion by the guide tongues and the adjusting rack. This interference with the moving rods requires the interpolation of an elastic intermediate member which fails, however, effectively to prevent slurring of the printing. Another fixing device for the adjusting lever in the form of a tooth attached to the adjusting and stop lever and engaging a fixed toothed member cannot insure a secure position of the type wheel, since the distance to the type and the springiness of the interposed parts render accurate fixing impossible. A typewriter whose type wheel is turned for adjusting the type to be printed and moved in locked position towards the platen to effect printing is known already, the wheel being advanced in guides. These guides consist, however, of a slide guided above the base plate by two members and having its axis disposed vertically to the base plate with the type wheel arranged on the axis at a relatively large distance from the slide. Furthermore, separate means are provided for adjusting and printing the types, and the means for printing causes also the locking of the adjustment of the type wheel. An arrange-

ment of this kind cannot insure accurate adjustment and guiding of the type to be printed.

According to the invention, the defects of the known machines are eliminated by arranging the guide of a slide plate carrying the type wheel and rectilinearly movable towards the platen directly in the base plate of the machine, in which is located also a toothed member for locking the type wheel in adjusted position, the teeth of said member being engaged during printing motion by a locking pin disposed on the underside of the adjusting rack. In this way, reliable fixing and guiding of the type wheel and a clear impression of the adjusted type will be attained by means of a greatly simplified construction employing a reduced number of parts, as the possibility of displacement or rotation of the type wheel as well as elastic intermediate members or parts that could cause inaccuracies has been avoided. According to the invention, this guiding of the type wheel is further utilized for effecting motion of the carriage in a very simple manner. For this purpose, a spring-actuated pawl is disposed on the slide plate carrying the type wheel so as to engage the carriage feed rack during motion of the slide plate to move the carriage for the width of one letter, and the spacing between the characters is effected by axially turning the adjusting lever and thus bringing a locking member connected therewith into the plane of the locking teeth so as to strike this toothed member and limit the travel of the slide plate in such a way that the carriage is moved but the type wheel cannot strike against the platen.

All parts of the machine disposed in front of the carriage including the type wheel are enclosed by a casing having a roof-like top. The upper oblique wall of this casing, which extends approximately vertically to the line of sight of the writer and renders the line to be written visible, is provided with a slot or transparent portion through which a mark of the adjusting rods can be seen and above and below which the letter and sign scales are preferably arranged.

This construction insures an extraordinarily convenient and rapid adjustment of the type to be printed without fatiguing hand and eye, especially as during the stroke the radial movement of the adjusting mark is not visible. The screening of the moving parts, the favorable arrangement of the scale and visible writing insure a considerable increase in writing speed compared with the known adjusting lever machines, the more so as the space key does not re-

quire a change in the position of the hand or additional keys but fits perfectly into the play of motions, since a slight turning of the adjusting knob will instantly and with absolute reliability 5 provide the desired spacing.

One form of the invention is illustrated in the accompanying drawings, in which Figure 1 is a diagrammatic view of the machine according to the invention with a portion of the front 10 covering and the adjusting scale removed to show the parts of the adjusting device disposed underneath; Fig. 2, a plan after removal of the carriage and the covering of the adjusting device; Fig. 3, a front view of the carriage; Fig. 4, 15 an end view thereof showing the left end; Fig. 5, a detail view showing the right hand end of the carriage; and Fig. 6, a view of a modified construction of a type wheel.

Referring to the drawings, the machine comprises the base plate 1 and two upright frame walls 2, 3 and the guide 4 for the carriage. In the walls 2, 3 a guide rod 5 is secured which carries a longitudinally displaceable and rotatable sleeve 7 provided with an edge-like adjusting mark 6. 20 The sleeve 7 has two downwardly extending arms 8 to the ends of which a rack 9 is secured. The rack 9 is in mesh with a gear 11 coupled with the type wheel 10 and rotatably arranged with the latter on a joint vertical shaft 12. The shaft 12 is with its lower end secured in the slide plate 13 which is disposed vertically to the direction of the guide rod 5 in a guide 14 in the base plate 1 and subjected to the action of a spring 15 which holds the plate 13 with the gear 11 and the type 25 wheel 10 in a front end position or always returns them to this position.

In the rack 9 a downwardly directed locking pin or tooth 16 is secured, opposite to which a toothed or notched locking plate or comb 17 is 30 firmly disposed in the base plate 1. One of the arms 8 of the slideable and rotatable sleeve 7 is fitted with a bush 18 which accommodates an adjusting lever 20. The lever 20 is rotatable and provided at its free end with a knob 19. At its 35 inner end, the adjusting lever 20 possesses a short lever arm 21 whose free end is articulated to a locking arm 22, the free end of which is broadened and guided in a slot of the rack 9. According to the adjustment of the arm 21 of the adjusting lever 20, the end of the locking arm 22 40 projecting from the under side of the rack 9 will be either in the plane of the toothed locking plate 17 and thus limit the feed of the rack 9 by a motion of the arm 8 or the locking arm 22 45 will be withdrawn to such an extent that it will not interfere with the feed of the rack 9.

Parallel to the guide rod 5 a shaft 23 is displaceably disposed in the walls 2, 3, as indicated in Fig. 2, which projects from the outside of a 50 wall to the extent of its displacement. The shaft 23 carries the pawls 24 for moving the ribbon spools, the pawls being pressed by a spring, not shown, which is arranged on the shaft 23, into the teeth of the spool feed gears 25 according to 55 the position of the shaft. The shaft 23 carries further a broad stop arm 26 which is struck by the shaft 12 of the type wheel 10 at each feed motion of the latter whereby the pawl shaft 23 is moved in one direction whereas the return of the 60 shaft is effected by means of the torsion spring, not shown.

The carriage guide 4 is provided with stepped stops 27 for limiting the motion of the carriage in one direction and with a stop 28 on the other side 75 for limiting carriage motion in the other direction

as well as with adjustable lever stops, not shown, on both front sides of the carriage. A paper guide plate 29 with feed rolls 30 and a shaft 31 is arranged in the walls 32 of the platen carriage and is pressed with the end of the roll against the roller 33 by torsion springs, not shown. By means of the pins 34 a paper support or table 35 is secured to the walls 32 of the frame, which with its downwardly directed extension 36 rests on the rear end of the paper guide plate 29, so that the roll end of the latter together with the rolls 30 can be moved away from the platen 33 by pushing back the paper table 35.

The carriage frame rests with a rack 37 secured to the under side thereof on a horizontal 15 guide formed by pin-like elevations 38 of the base plate 1. At each stroke of a type the carriage is moved by a pawl 40 articulated to a lateral extension 39 of the slide plate 13 and held in position by a tension spring 41. The pawl 40 forms with the extension 39 of the slide plate 13 a toggle lever which is spread during the feed of the plate 13 up to the moment of engagement with the rack 37 and then collapses so as to bring about the motion of the carriage.

Return of the carriage is effected by a pawl 42 articulated to the base plate 1 on the other side of the slide plate 13 and displaceably guided on a fixed hinge bolt 44 by means of the slot 43. The pawl 42 is controlled and held in position by a tension spring 45 and a tension member 47 connected with a back space key 46, the spring 45 and the member 47 engaging a short arm 48 of the pawl, and the length of the tension member 47, which is flexible, is dimensioned so that the spring 45 will hold the pawl in the one end position of the slot 43. When the back space key 46 is depressed, the pawl 42 is first moved about the hinge pin 44 to engage the rack 37 and then displaced parallel to the carriage guide as soon as 40 engagement is effected.

The type wheel 10 can be raised and lowered on its shaft 12 and a coupling pin 49 connecting the shaft with the gear 11 by means of a cranked shaft 50 which is movably disposed in the wall 2 and the boss 51 of the frame of the machine and fitted with the shift keys 52, 53. The stroke of these keys as well as that of the back space key 46 can be accurately regulated by means of screwed-in stop screws 54.

The walls 2, 3 of the machine frame have roof-shaped tops as stated and serve for receiving the roof-shaped covering of the type adjusting and printing device. This covering consists of a front vertical wall 55 and an upper obliquely ascending 55 wall 56. The vertical wall 55 contains clearances for the shift keys 52, 53 and the back space key 46 as well as a slot, not shown, for the passage of the adjusting lever 20. In the inclined wall 56 a double scale 57, 58 with an interposed window 59 is provided to render the adjusting mark 6 60 visible.

The oblique wall 56 is disposed approximately 65 vertically to the line of sight.

Better visibility of the lines of writing will be insured by a type wheel as shown in Fig. 6 having the form of a truncated cone with the base on top, as the line will then appear slightly above the horizontal central plane of the platen.

According to the invention, the main parts of the machine, especially the base plate, the parts of the frame and the roof-like covering, are made from artificial materials, such as artificial resin, that can be formed by pressing. To further reduce weight and noise other parts like the type 70 75

frame, the adjusting gear, the carriage locking gear and the ribbon rolls with the transport toothing may be produced as pressed or cast pieces from artificial materials of the kind indicated.

In order to operate the machine, the button 19 is grasped with the lever 20 in its raised position and the member 22 is lifted by rotating the button. The frame formed by the members 7, 8, 10 and 9 is now moved along the rod 5 until the index 6 is positioned in front of the character on one of the scales 57 and 58 which it is desired to print. As the rack moves longitudinally of the rod 5, the type wheel 10 is caused to rotate by 15 the engagement of the rack 9 with the gear 11 at the bottom of the type wheel 10 and the character selected is brought into alignment with its printing position in front of the platen 33. As 20 shown in Figure 6, the normal position in elevation of the type wheel is such as to print a character (lower case) in the upper or first row of characters. If the character to be printed lies in the second or middle row (capitals) or in the third or bottom row (numerals and punctuation marks) 25 the appropriate key 52 or 53 is depressed to raise the type wheel on its shaft and thus to bring the desired character into printing position. The button 19 is now depressed. This rocks the frame members 7, 8, and 9, on the rod 5 and causes the gear 11 on the type wheel shaft to move rearwardly and carry the type wheel with it so that the proper type character strikes the ribbon and carries it against the paper on the platen 33. 30 The type wheel is guided for rectilinear movement by the bar 13. As the gear 11 is thus moved, the pin 16 enters between two of the teeth on the fixed comb 17 so that proper alignment of the type with the place at which it is to 35 strike is effected. Likewise, as soon as the frame starts to rock, no further sliding movement can 40 take place along the rod 5 because of the engagement of pin 16 and comb 17. As the shaft 12 is moved toward the platen it engages the arm 26 45 so that the shaft 23 is rocked and this causes the engaged pawl 24 to rotate the ratchet 25 with which it engages so that the ribbon is fed along as is common in typewriters. Furthermore, rearward movement of the slide 13 causes the pawl 50 40 to bias and thus move the rack 37 and carriage one space to the left.

I claim:—

1. A type wheel typewriter, comprising, in combination, a base plate, upright side walls on said plate for forming the machine frame, a carriage and platen, a guide for said carriage on said base plate, a guide rod mounted in said side walls, a sleeve longitudinally displaceably and rotatably guided on said rod, an adjusting mark on said sleeve, two downwardly directed arms on said sleeve, a rack secured to the free ends of said arms, a guide in said base plate, a slide plate disposed in said guide and transversely movable relative to said platen and guide rod, a vertical shaft secured with its lower end in said guide plate, a type wheel, a gear on the lower end of said type

wheel and rotatably disposed therewith on said vertical shaft, said gear being in mesh with said rack, means for raising and lowering the type wheel, means for holding said slide plate with said gear and type wheel in front end position and returning it thereto, a lever movable parallel to the platen for turning and displacing said type wheel to adjust and print a type, said lever being carried by one of said arms, a downwardly extending locking pin on the underside of said rack, and a toothed plate firmly arranged in said base plate, said locking pin engaging said toothed plate during the printing motion to secure said type wheel in adjusted position. 5 10

2. A type wheel typewriter according to claim 1, comprising a locking arm and means for connecting said arm with the lever, said arm being adapted to be brought into engagement with the toothed plate by the lever to limit the travel of the slide plate and thus prevent the type wheel from striking the platen during the motion of the carriage. 15 20

3. In a typewriter of the class having a type wheel and operating means for the type wheel including an operating lever mounted for sliding and swinging movement and an indicator sliding with the lever; a base, a carriage mounted to move transversely of the base, a platen supported on said carriage, and a casing at the front of the typewriter covering the type wheel and having a longitudinal sight slot wherethrough the indicator may be observed.

4. In a typewriter of the class having a type wheel and operating means for the type wheel including an operating lever mounted for sliding and swinging movement and an indicator sliding with the lever; a base, a carriage mounted to move transversely of the base, a platen supported on said carriage, a casing at the front of the typewriter covering the type wheel and having a longitudinal sight slot wherethrough the indicator may be observed, and character scales on the casing extending longitudinally beside said slot.

5. In a typewriter of the type wheel class having a shaft and type wheel therein, a base, a slide bar mounted on said base to slide forwardly and backwardly thereon in a rectilinear path, said bar forming a support for the shaft and type wheel, a carriage mounted at the rear of said base to slide transversely thereof, a rack fixed to said carriage and extending longitudinally thereof, means to actuate said bar, said type wheel having a plurality of rows of type, a crank shaft supported from said base for rocking movement, said crank shaft having a crank engaging the under side of the wheel, and manually operable means to rock the shaft selectively through a plurality of angles. 45 50 55

6. A type wheel for typewriters of the type wheel class including a body in the form of a truncated cone having its major base uppermost, and type characters carried on said body and extending in peripheral rows therearound. 60
